Primary Examiner — Melanie Pellegrini(74) *Attorney, Agent, or Firm* — Stern & Schurin LLP(57) **CLAIM**

The ornamental design for an article of jewelry, as shown and described.

DESCRIPTION

FIG. 1 is a top, front and right side perspective view of an article of jewelry showing my new design; and,
 FIG. 2 is a front elevational view thereof.

The broken lines showing a female figure represent environment and the remaining broken lines represent portions of the article of jewelry which form no part of the claimed design.

1 Claim, 2 Drawing Sheets(56)
